Attorney

UNITED STATES PATENT OFFICE.

JOSEPH J. BIMLER, OF MICHIGAN, NORTH DAKOTA.

COAL SCUTTLE.

Application filed December 16, 1922. Serial No. 607,348.

To all whom it may concern:

Be it known that I, JOSEPH J. BIMLER, a citizen of the United States, residing at Michigan, in the county of Nelson and State 5 of North Dakota, have invented certain new and useful Improvements in Coal Scuttles, of which the following is a specification, reference being had to the accompanying drawings.

- 10 This invention relates to improvements in coal scuttles, and an important object of the invention is to provide a scuttle which is capable of use in handling both hard and soft coal.
- 15 As is well known to those familiar with the art, a scuttle for use in handling hard coal where the lumps are comparatively small must be provided with a hood, as otherwise in pouring the coal from the scuttle there is a tendency of the entire surface 20 of the coal to shift resulting in overrunning of the coal from the sides of the spout or wall and a consequent spilling of the same. With soft coal, however, it is necessary that 25 the scuttle be free from such a hood for the reason that soft coal often contains large lumps which would not pass through the restricted aperture formed by the hood and which must be broken up before they 30 can be used in the scuttle, requiring considerable labor and to a certain extent lessening the value of the coal, particularly in use in a grate or the like, due to the fact that these large lumps burn very freely and 35 more slowly than the finely broken or dust coal. It is accordingly an object of this invention to provide a scuttle having a hood which is pivoted and which may accordingly be moved into or out of operative position, thus permitting the use of the scuttle 40 for either type of coal.

A further disadvantage of the scuttle as ordinarily constructed is that in tilting the same to discharge the contents thereof, the shifting of the coal within the scuttle causes a change of the center of gravity within the bucket and the comparatively long handle ordinarily applied to these scuttles permits the scuttle to rotate or shift to such a point 50 that it becomes overbalanced, resulting in a deposit upon the fire greater than desired and possibly in the loss of the entire contents of the scuttle.

An important object of this invention is 55 to further provide means for controlling the motion of the scuttle during the tilting

operation which is independent of such handle and which is more rigidly connected with the body of the scuttle and the handle so that the loss of control for the reasons above 60 set forth is prevented.

These and other objects I attain by the construction and arrangement shown in the accompanying drawings wherein for the purpose of illustration is shown a preferred 65 embodiment of my invention and wherein like reference characters designate like parts throughout.

In the drawings:

Figure 1 is a side elevation partially 70 broken away of a coal scuttle embodying a hood constructed in accordance with my invention;

Figure 2 is a perspective view of the 75 hood detached; and

Figure 3 is a detail sectional view showing the hood receiving indentations.

Referring now more particularly to the drawings, the numeral 10 indicates the scuttle body, 11 the spout portion thereof and 12 the bail, which bail is pivotally connected with the body portion at a point approximating the center of gravity of the scuttle when filled with coal. In accordance with my invention, I provide an arched hood 80 member 13 shaped to fit the spout 11 of the scuttle in the upper end thereof. This hood is formed of a piece of sheet metal curved and having at its rear lower edges pivotal engagement, as at 14, with the scuttle adjacent the pivot point of the bail 12 thereof. This rear edge may, if desired, be reinforced by a steel wire 15 which is secured to the rear edge of the sheet from which the hood is formed by rolling the same 95 thereon, as indicated at 16. The ends of this wire will project beyond the sides of the sheet and will have eyes 17 formed therein for the reception of the pivots upon which the hood is to be mounted.

The forward edge of the hood is notched, as indicated at 18, and the metal at the edges of this notch has attached thereto by rolling, a resilient steel wire 19 which is hooked at both ends to thereby provide oppositely 105 extending portions 20. The notch 18 faces the front or outlet wall 21 of the spout 11, and the side walls of the spout at their upper ends and adjacent such outlet wall 21, have each formed therein an opening 22. The spout in its construction is so formed 110 that the forward end thereof, as maintained

in position by the included wire 19, is of greater width than the internal width of the spout so that it is necessary to compress the forward ends of the spout to permit engagement of the oppositely extending hooked ends 20 in these openings. For this purpose, the spout is provided adjacent the edges of these openings at the forward portions of the hood with indentures 23 in which the fingers may be engaged to perform such compressing operation. It will be seen that when the spout is swung about its pivot while compressed that the hood may be entered within the spout 11 and that upon release of the same the hooked ends 20 will engage in the openings 22 firmly holding the hood in the closed or normal position. When it is desired to release the same, this may be done by engaging the spout and again compressing the same.

The hood 13 is provided centrally thereof adjacent its rear edge with an upstanding handle 24. By engaging this handle with the hood closed, a solid engagement of each hand with the scuttle can be assured so that there will be no accidental discharge of the contents thereof, it being understood that the scuttle will be provided upon the body with the usual hand hold 25 arranged at the rear end thereof. When the scuttle hood 13 is released at its forward end to permit the pouring of large lumps from the scuttle, the hood 13 with its handle 24 becomes a comparatively short bail for supporting the scuttle during the pouring operation and accordingly the likelihood of accidental discharge of an excessive amount of the contents is prevented.

From the foregoing it is believed to be obvious that a scuttle provided with a hood such as described is possessed of many advantages not possessed by the ordinary type of scuttle and may be used with either type of fuel as desired. It will, furthermore, be obvious that the construction thereof as hereinbefore set forth is capable of some change and modification without materially departing from the spirit of my invention and I accordingly do not limit myself to such specific structure except as hereinafter claimed.

I claim:

1. In combination with a scuttle having a pouring spout and the usual pivoted bail, a hood therefor pivoted to the scuttle adjacent the pivot of the bail and having a resiliently expanded forward end of greater width than the pouring mouth of the scuttle, openings formed in the side walls of the pouring mouth adjacent the forward ends thereof, and catches rigidly secured to the sides of the forward end of the hood and adapted for engagement in said openings.

2. In combination with a scuttle having a pouring spout and the usual pivoted bail,

a hood therefor pivoted to the scuttle adjacent the pivot of the bail and having a resiliently expanded forward end of greater width than the pouring mouth of the scuttle, openings formed in the side walls of the pouring mouth adjacent the forward ends thereof, and catches rigidly secured to the sides of the forward end of the hood and adapted for engagement in said openings, said hood being provided centrally thereof adjacent its rear edge with a handle.

3. In combination with a scuttle embodying a pouring spout and the usual pivoted bail, an arched hood conforming substantially to the shaping of the spout at its upper end and pivoted at its rear end to the scuttle adjacent the pivots of said bail, openings formed in the side walls of the pouring spout of the scuttle adjacent the front wall thereof, said hood including at the forward edge thereof a resilient expanding medium normally expanding the same to a width greater than the width of the pouring spout at its forward end, and catches carried by said hood at its forward end and adapted for engagement in the openings of the side walls of the spout.

4. In combination with a scuttle embodying a pouring spout and the usual pivoted bail, an arched hood conforming substantially to the shaping of the spout at its upper end and pivoted at its rear end to the scuttle adjacent the pivots of said bail, openings formed in the side walls of the pouring spout of the scuttle adjacent the front wall thereof, said hood including at the forward edge thereof a resilient expanding medium normally expanding the same to a width greater than the width of the pouring spout at its forward end, and catches carried by said hood at its forward end and adapted for engagement in the openings of the side walls of the spout.

5. In combination with a scuttle embodying a pouring spout and the usual pivoted bail, an arched hood conforming substantially to the shaping of the spout at its upper end and pivoted at its rear end to the scuttle adjacent the pivots of said bail, openings formed in the side walls of the pouring spout of the scuttle adjacent the front wall thereof, said hood including at the forward edge thereof a resilient expanding medium normally expanding the same to a width greater than the width of the pouring spout at its forward end, catches carried by said hood at its forward end and adapted for engagement in the openings of the side walls of the spout, said hood being provided at its forward end at opposite sides thereof with indentures forming hand holds for engagement in compressing said hood against the action of said holding member.

opposite sides thereof with indentures forming hand holds for engagement in compressing said hood against the action of said holding member, and a hand hold carried by said hood centrally thereof and adjacent its rear edge.

6. In combination with a scuttle embodying the usual pouring spout and bail, a hood therefor comprising a sheet of metal curved 10 to form an arch and having substantially the same shape when viewed in plan as the upper end of the spout of the scuttle, said sheet of metal having rolled in the front and rear edges thereof wires having their 15 ends projecting beyond the edges of the sheet, the wire at the rear edge of the sheet having the projecting ends thereof formed with eyes for the reception of pivots extending through the walls of the scuttle, the 20 side walls of the pouring spout being provided adjacent the upper forward edges thereof with openings, the wire in the forward edge of said sheet being provided with hooked ends adapted for engagement in said 25 openings.

7. In combination with a scuttle embodying the usual pouring spout and bail, a hood therefor comprising a sheet of metal curved to form an arch and having substantially the same shape when viewed in plan as the 30 upper end of the spout of the scuttle, said sheet of metal having rolled in the front and rear edges thereof wires having their ends projecting beyond the edges of the sheet, the wire at the rear edge of the sheet 35 having the projecting ends thereof formed with eyes for the reception of pivots extending through the walls of the scuttle, the side walls of the pouring spout being provided adjacent the upper forward edges 40 thereof with openings, the wire in the forward edge of said sheet being provided with hooked ends adapted for engagement in said openings, the last named wire being resilient and normally expanding the forward 45 end of the hood to a width greater than the width of the forward end of the spout.

In testimony whereof I hereunto affix my signature.

JOSEPH J. BIMLER.
